Primary Examiner — Janice Hallmark*Assistant Examiner* — Adedoyin Taiwo Odeyale(74) *Attorney, Agent, or Firm* — Schroeder & Siegfried, P.A.(57) **CLAIM**

The ornamental design for a septic chamber, as shown and described.

DESCRIPTION

FIG. 1 is a front perspective view of a septic chamber showing my new design;

FIG. 2 is a rear perspective view thereof;

FIG. 3 is a top plan view;

FIG. 4 is a bottom plan view;

FIG. 5 is a right side elevational view;

FIG. 6 is a left side elevational view;

FIG. 7 is a rear elevational view; and,

FIG. 8 is a front elevational view.

Broken lines illustrate portions of the septic chamber that form no part of the claimed design.

1 Claim, 7 Drawing Sheets# US D1,036,616 S
